UNITED STATES PATENT OFFICE

JOHN J. COLLINET, OF CHICAGO, ILLINOIS, ASSIGNOR TO DRYING SYSTEMS, INC., OF CHICAGO, ILLINOIS, A CORPORATION OF ILLINOIS

TOGGLE CLAMP

Application filed January 4, 1930. Serial No. 418,504.

This invention relates to clamps of the type employed in stretching leather on a frame and drying the same.

The main objects of this invention are to provide an improved form of toggle clamp particularly adapted for gripping and stretching leather and of a construction that is both inexpensive and durable; to provide an improved form of toggle spring and spring mounting in devices of this kind, whereby a comparatively light spring may be utilized for effectively urging the clamping jaws into engaged position while at the same time providing an extremely sensitive action that enables the clamps to be engaged and disengaged from the work with a minimum of effort on the part of the workmen; and to provide a clamp of this kind wherein the spring can be readily replaced without dismantling the device or otherwise disturbing the relation of the parts.

A specific embodiment of this invention is illustrated in the accompanying drawings in which:

25 Fig. 1 is a perspective view of a leather stretching toggle clamp constructed according to this invention.

Fig. 2 is a longitudinal section taken on a medial vertical plane, and showing the parts in the positions which they occupy when the clamping jaws are engaged.

Fig. 3 is a similar section showing the relation of the parts when the jaws are disengaged.

35 Fig. 4 is a fragmentary section taken on the line 4—4 of Fig. 2.

Fig. 5 is a small-scale development of the plate from which the body is formed.

In the form shown the clamp comprises 40 a frame 1 having a fixed jaw 2 at its front end with a cam-shaped movable jaw 3 opposed thereto, said jaws being located at the front end of the frame. The rear end of the frame has a loop 5 which provides a 45 finger hold whereby the operator may grip the clamp. A toggle spring 6 has its front end loosely seated in a clevis 7 which is pivotally connected by a pin 8 with the bifurcated rear end of the movable jaw 3. A second clevis 9 which is of U-shape, has a seat

10 in which the rear end of the spring 6 is held and has its arms connected by a pivot pin 11 with the frame.

The movable jaw 3 has a cam surface 12 opposed to the jaw 2 and is pivoted at its front end by means of integral lugs 13. The cam surface 12 is serrated or provided with teeth shaped to engage the leather or other sheet that is interposed between the jaws, and is so related to the pivotal connection 13 that the friction and pull of the work will tend to tighten the grip of the jaws.

The jaw 3 is moved into and out of its engaged position by means of a lever 14 which is pivoted at 15. The lever 14 is preferably made of a piece of sheet metal bent as illustrated with a pair of spaced arms 16 which are slotted to receive the ends of the pivot pin 8 and with a handle 17 which lies along the finger hold 5 in position to be engaged by the thumb of the operator.

The frame 1 is preferably made of a single piece of sheet metal cut to suitable form and bent upon itself to provide the finger hold 5 and portions which form the top plate 18 and jaw 2 and a bottom plate 19. The portion which forms the bottom plate 19 has wings or cheek pieces 20, which are folded up at the sides to complete a box-like body. The cheek pieces are provided with forwardly extending portions 21 which overlie the edges of the jaw 2 and effectively brace the same. The cheek pieces 20 are also provided with perforations to receive the pivot lugs 13 and the pins 11 and 15. These pins 11 and 15 are peened at their ends to form heads which lock the cheek pieces in place and an additional rivet 22 may be inserted between the cheek pieces above the top plate 18 for additional strength. The top plate 18 is cut away at each side to permit the passage of the arms 16 of the lever 14. A hook 23 is struck out of the bottom plate 19 whereby the clamp may be attached to the stretcher frame which is not shown in the drawings but which comprises a perforated plate or screen with apertures to receive such hook.

In operation a plurality of such clamps is secured around the edges of the sheet of

leather and hooked into the supporting frame to stretch the leather.

- The operator puts his forefinger through the loop 5 of the clamp and pushes the lever 14 upward with his thumb to open the jaws.
- 5 The toggle spring holds the jaw 3 in its disengaged position until the edge of the sheet of leather is inserted between the jaws and the operator depresses the handle 17 of the lever to cause the jaws to engage the leather.
- 10 Through the toggle action of the spring 6, said spring now holds the jaws engaged, and the hook 23 is inserted in a convenient aperture in the stretcher frame.
- 15 The clevis 10 provides a bearing for the spring 6 somewhat rearward of the pivot 11 and thus permits the use of a long and sensitive spring for controlling the action of the toggle with the same result as if it were a 20 toggle link extending directly between the pivot 11 and the pivot 8.

Since the two ends of the spring 6 are loosely seated in their respective clevises, it is quite a simple operation to insert or remove the 25 spring 6 without disturbing any of the rest of the assembly. All that is necessary to insert the spring is to insert the front end of it into the clevis 7, spring it to bowed form and drop the rear end into the seat 10 in the clevis 9.

30 The spring locks itself into position and there is no possible danger of its becoming dislodged except when it is to be intentionally removed.

Although but one specific embodiment of 35 this invention has been herein shown and described, it will be understood that details of the construction shown may be altered or omitted without departing from the spirit of this invention as defined by the following 40 claims.

I claim:—

1. A toggle clamp comprising a frame having a fixed jaw, a pivoted jaw on said frame coacting with said fixed jaw and having a 45 cam-shaped gripping surface, a toggle link cooperating with said pivoted jaw and frame and comprising a leaf spring and clevises carrying the ends of said spring and pivotally mounted respectively on said pivoted jaw and frame, and means for shifting said pivoted jaw into and out of its engaged position.
2. A clamp comprising a frame having a fixed jaw, a cam opposed to said jaw and eccentrically pivoted on said frame, a clevis pivoted to said cam, a second clevis pivoted to said frame rearward of said cam, a leaf 55 spring seated in said clevises and acting in toggle relation with said cam for holding the same in engaged and disengaged position, and means for shifting said cam.
3. A clamp comprising a frame having a fixed jaw, a cam opposed to said jaw and eccentrically pivoted on said frame, a clevis pivoted to said cam, a second clevis pivoted 60 to said frame rearward of said cam, a leaf

spring seated in said clevises and acting in toggle relation with said cam for holding the same in engaged and disengaged positions, a looped finger hold on said frame, and a lever extending adjacent to said finger hold and pivoted on said frame and cooperating with said cam for shifting said cam.

4. A clamp comprising a frame having a fixed jaw, a cam opposed to said jaw and eccentrically pivoted on said frame, a clevis pivoted to said cam, a second clevis pivoted to said frame rearward of said cam, a leaf spring seated in said clevises and acting in toggle relation with said cam for holding the same in engaged and disengaged positions, a looped finger hold on said frame, and a lever extending adjacent to said finger hold and pivoted on said frame on a center separate from the pivotal connection of said last-named clevis and cooperating with said cam and having a handle for shifting said cam.

5. A clamp comprising a frame having a fixed jaw, a movable jaw pivoted on said frame and having a cam surface coacting with said fixed jaw, a toggle spring pivotally connected at its front end to said movable jaw, a clevis providing a seat for the rear end of said toggle spring and pivoted to said frame at a point in front of said rear end, and a lever pivoted on said frame having an arm engaging the pivotal connection between said movable jaw and toggle spring and having a handle for operating said movable jaw.

6. In a toggle clamp, a frame provided with a fixed jaw, a movable jaw pivoted to said frame, a toggle spring having one end thereof bearing on said movable jaw, and a clevis providing a shiftable seat for the other end of said spring, said clevis being pivotally supported on said frame at a point intermediate the ends of said spring.

7. A clamp comprising a frame having a fixed jaw, a jaw movably mounted upon said frame for cooperation with said fixed jaw, a handle connected to the frame and the movable jaw for shifting the movable jaw toward and away from the fixed jaw, a toggle spring having one end attached to the movable jaw, and means shiftable mounted upon said frame engaging the opposite end of said spring.

Signed at Chicago this 21st day of December 1929.

JOHN J. COLLINET.
